UNITED STATES PATENT OFFICE.

PHILIP G. AULSON, OF SALEM, MASSACHUSETTS.

FRAME FOR LEATHER-SPRAYING DEVICES.

Application filed August 5, 1927. Serial No. 210,896.

This invention relates to mechanism for supporting a spraying device and also the article to be sprayed, one object of the invention being the provision of means whereby the spraying device may be manually moved on horizontal guides and said horizontal guides raised and lowered on vertical guide members.

A further object of the invention is the provision of means whereby the vertically movable carriage may be locked to the vertical guide members by bolts extending into sockets in said guide members.

Another object is the provision of means whereby said vertical guide members may be rotated about their axes to place new sets of bolt sockets in position to coact with the locking bolts of said carriage, each guide member having a plurality of vertical sets of sockets, the sockets in each vertical set being spaced apart differently from those of the other sets.

Yet another object of the invention is the provision of means whereby the article to be sprayed may be disposed at different distances from the rear of the main frame carrying the spraying device.

These objects and others are attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings:

Figure 1 represents a front elevation of an apparatus embodying the principles of the present invention.

Figure 2 represents a horizontal section of same on line 2, 2, on Fig. 1.

Figure 3 represents a front elevation of a portion of one of the side posts with one end of the travelling carriage movable vertically thereon, said view being drawn to an enlarged scale.

Figure 4 represents a side elevation of the same with the connecting rods and tubes of the carriage in section.

Figure 5 represents a vertical section of the upper end of the frame on line 5, 5, on Fig. 1.

Figure 6 represents a vertical section of same on line 6, 6, on Fig. 5.

Figure 7 represents a front elevation of the horizontally moving air-brush-support, portions of the air brush being in section.

Figure 8 represents a side elevation of the same with portions thereof in section, and

Figure 9 represents a vertical section on line 9, 9, on Fig. 1 showing the lower end of one of the side posts and parts connected therewith, portions of the supporting base being in section.

Similar characters indicate like parts throughout the several figures of the drawings.

In the drawings 10, 10 are bases preferably secured to the floor and tied together by a bar 11.

Each base 10 has an upwardly extending hub 12 in which is revolvably mounted the lower end 14 of a vertical guide member 13 which is preferably cylindrical with said lower end 14 reduced in diameter.

The lower end 14 is provided with a plurality of depressions 15 equally spaced in the same horizontal plane about the periphery thereof.

A locking member 16 is provided for each base 10, this member being threaded to the hub 11 and having a reduced end 16* adapted to enter a depression 15 and retain said guide member in position when it has been adjusted about its axis.

Each guide member has a plurality of vertical sets of radial sockets 17 formed therein, the sockets 17 of each vertical set being equally spaced apart and the spacing of the sockets in each set varying from the spacing of the sockets in each of the other sets.

Pinned to each guide member 13 are two collars 18 between which is disposed a hub 19 of a bracket 20 extending rearwardly from said guide member 13.

The brackets 20 of the two guide members 13 are tied together by rods 21 and 22 and from the rod 22 extend struts 23 the lower end of each of which is connected at 24 to an ear 25 formed upon a base 10.

Extending upwardly from the bracket 20 are a plurality of spaced pins 26 between which a frame 27 is adapted to be positioned.

This frame may be of any desired construction but preferably is made of a wood panel

with its edges enclosed in metal as indicated at 28.

To the wooden panel 27 may be secured in any well known manner a hide 29 or other article to which it is desired to apply a spray of pigment.

The upper end 30 of each vertical guide member 13 is reduced in diameter as indicated in Fig. 6 and surrounding this reduced end 30 is a hub 31 having a lateral projection 32, the projections 32 of the hubs 31 at the top of the two vertical guide members 13 being tied together by the channel iron 33, the ends of which are riveted to said projections 32 as indicated in Fig. 5 at 34.

The reduced end 30 is provided with an annular peripheral groove 35 into which extends the reduced end of the threaded member 36, thereby preventing the accidental displacement of the hub 31 from the vertical guide member 13.

The hub 31 is also provided at the front and rear thereof with ears 37 from which braces 38 extend upwardly at an angle to the ceiling where their upper ends are fixedly secured in position.

The hub 31 also has ears 39 extending upwardly therefrom between which are disposed grooved rollers 40 revoluble about pins 41 positioned in said ears 39.

Beneath each hub 31 is a collar 42 pinned to the guide member 13 and between the collar 42 and the hub 31 is a hub 43 having a rearwardly extending arm 44 provided with a plurality of downwardly extending pins 45 corresponding in number with and oppositely disposed to the pins 26 on bracket 20.

These pins 45 serve as guides for the upper end of the frame 27.

40 The frame 27 may be disposed between corresponding pairs of pins 26-45 to vary the distance of the frame 27 from the rear of the vertical guide members 13.

45 The two arms 44 are tied together at their outer ends by the rod 46 and each arm 44 has riveted thereto at 47 a bar 48, the opposite end of which is riveted to the angle iron 33 at 49.

By the construction described a rigid front framework is provided which has mounted 50 thereon means whereby the article to be sprayed may be positioned at various distances from the rear of said framework.

Extending over each pair of rollers 40 is a flexible member 50 to one end of which is secured a weight 51 while the opposite end is secured to a roller carrying member 52, each end of which is bifurcated and provided with a pin 53 on which is revolubly mounted a roller 54.

60 The rollers 54 have peripheral grooves fitting the peripheries of the vertical guide members 13 over which they are adapted to travel.

65 Each member 52 is provided with two depressions 55 in which rest the ends of the

tubes 56 and the two members 52 are tied together by the rods 57 extending through the tubes 56 thus forming a rigid carriage adapted to be moved freely lengthwise of the guide members 13 and carry therewith a spraying device.

Each member 52 is provided with a hub 58 through which extends a locking bolt 59, the outer end of which is adapted to enter a socket 17 and lock the carriage from vertical movement.

The bolt 59 has a collar 60 pinned thereto against which the spring 61 acts to force the bolt outwardly, the outward movement being limited by the collar 62 pinned to said bolt 59 and normally contacting with the end of the hub 58.

The inner end of each bolt 59 is provided with a perforated head 63 to which is secured one end of a flexible member 64 which member 64 extends through an opening 65 in a spider 66 forming a support for the spraying device 67 only a portion of which including the nozzle 68 is indicated in the drawings.

As the spraying device itself forms no part 90 of the present invention it is deemed unnecessary to illustrate the same in detail.

The spider 66 is preferably provided with four pairs of legs the outer ends of each pair having mounted therein a pin 69 on which 95 revolves a roller 70.

Each roller 70 is provided with a peripheral groove fitting the periphery of a tube 56 along which the support 66 is adapted to travel horizontally.

The spider or support 66 has a downward extension 71 provided with a vertical socket in which is rotatably mounted a pin 72 having an annular groove 73 into which extends the end of a screw 74 threaded to said extension. 105

This pin 72 is part of the spraying device holder 75 which is made in two parts, the part 76 being removable to permit the positioning of the member 77 and hook 78 of the spraying device 67 between said parts 75, 76. When 110 thus positioned these members are clamped between said parts 75, 76 by means of the screws 79 and nuts 80.

The hook 78 partially surrounds the hubs 81 formed upon the two parts 75, 76 of the 115 spraying device holder. The spraying device holder may be oscillated manually about the axis of pin 72.

In using this spraying device the hide 29 or other article to be sprayed is properly positioned at the rear of the main framework and the spraying device 67 is positioned at the top of the hide with the bolts 59 in two of the sockets 17.

The support 66 is then moved horizontally 125 along the tubes 56 with the spraying device 67 in commission and an even distribution of spray in a straight path will result.

The operator then by means of the flexible member 64 releases the bolts 59 from said 130

sockets 17 and moves the carriage downwardly to permit the bolts to engage with the next lower sockets 18 and the horizontal movement of the spraying device is repeated.

5 The weights 51 are so constructed as to counterbalance the weight of the vertically movable carriage and the parts supported thereby.

If it is desired to vary the locking position 10 of the vertically movable carriage the operator releases the locking members 16 and rotates both of the vertical guide members until other and similar sets of sockets 17 are in position to coact with the bolts 59 of the vertically movable carriage.

Any usual means for indicating the proper adjustment of the rotatable vertical guide members 13 may be used.

By the use of this improved spraying machine an even distribution of pigment may 20 be deposited over the entire surface of the article being treated and this distribution may be varied at the will of the operator.

Heretofore, where pigments have been applied by an air brush held in the hand of the operator the operator soon becomes very tired and has to rest.

Moreover, when the pigment is thus applied it is impossible for the operator to so 30 direct the air brush as to give an even distribution of the pigment and the hide when treated has a very streaked appearance as a consequence.

This objection is wholly overcome by using 35 the spraying machine described as the sprayer 67 is restricted to regular paths and the spray of pigment upon the hide is evenly distributed.

Another advantage is that while the sprayer 40 is moved manually the operator does not sustain the weight thereof, this weight being sustained by the counter weights 51.

It is believed that the operation and many 45 advantages of the invention will be well understood without further description.

Having thus described my invention, I claim—

1. The combination of two vertical guide members; a carriage movable vertically thereon; means for locking the opposite ends of 50 said carriage directly to said guide members; and an air brush support movable horizontally on said carriage.

2. The combination of two vertical guide members; a carriage movable vertically thereon; means for locking the opposite ends of 55 said carriage directly to said guide members; an air brush support movable horizontally on said carriage; and means secured to the rear of said guide members for vertically supporting an article to be sprayed.

3. The combination of two vertical guide members; a carriage movable vertically thereon; means for locking the opposite ends 60 of said carriage directly to said guide mem-

bers; an air brush support movable horizontally on said carriage; and means secured to the rear of said guide members for vertically supporting an article to be sprayed at different distances from said air brush support. 70

4. The combination of two vertical guide members; a carriage movable vertically thereon; means for locking the opposite ends of said carriage directly to said guide members; an air brush support movable horizontally on said carriage; brackets extending rearwardly from the upper and lower ends of said guide members; and means for positioning an article supporting frame in vertical position on said brackets. 75

5. The combination of two vertical guide members; a carriage movable vertically thereon; means for locking the opposite ends of said carriage directly to said guide members; an air brush support movable horizontally on said carriage; brackets extending rearwardly from the upper and lower ends of said guide members; a plurality of pins projecting from each bracket; and means for vertically positioning an article supporting 80 frame on said brackets between said pins. 85

6. The combination of two vertical guide members provided with a plurality of vertical sets of bolt sockets, the sockets in each vertical set being spaced apart differently from those in the other sets; bearings for the ends of said guide members in which said members may be rotated about their vertical axes; a carriage movable vertically between said guide members; spring-pressed bolts at 90 the opposite ends of said carriage adapted to coact with said sockets; means for withdrawing said bolts; and an air brush support movable horizontally on said carriage. 95

7. The combination of two vertical guide members provided with a plurality of vertical sets of bolt sockets, the sockets in each vertical set being spaced apart differently from those in the other sets; bearings for the ends of said guide members in which said members may be rotated about their vertical axes; a carriage movable vertically between said guide members; spring-pressed bolts at 100 the opposite ends of said carriage adapted to coact with said sockets; means for withdrawing said bolts; and an air brush support movable horizontally on said carriage. 105

8. The combination of two vertical guide members provided with a plurality of vertical sets of bolt sockets, the sockets in each vertical set being spaced apart differently from those in the other sets; bearings for the ends of said guide members in which said members may be rotated about their vertical axes; a carriage movable vertically between said guide members; spring-pressed bolts at 110 the opposite ends of said carriage adapted to coact with said sockets; means for simultaneously withdrawing said bolts; and an air brush support movable horizontally on said carriage. 115

support movable horizontally on said carriage; and means in the rear of said carriage for supporting the article to be sprayed.

9. The combination of two vertical guide members provided with a plurality of vertical sets of bolt sockets, the sockets in each vertical set being spaced apart differently from those in the other sets; bearings for the ends of said guide members in which said members may be rotated about their vertical axes; a carriage movable vertically between said guide members; spring-pressed bolts at the opposite ends of said carriage adapted to coact with said sockets; means for simultaneously withdrawing said bolts; an air brush support movable horizontally on said carriage; and means supported and extending rearwardly from said guide members adapted to support an article to be sprayed.
10. The combination of two vertical guide members provided with a plurality of vertical sets of bolt sockets, the sockets in each vertical set being spaced apart differently from those in the other sets; bearings for the ends of said guide members in which said members may be rotated about their vertical axes; a carriage movable vertically between said guide members; spring-pressed bolts at the opposite ends of said carriage adapted to coact with said sockets; means for simultaneously withdrawing said bolts; an air brush support movable horizontally on said carriage; brackets supported by and extending rearwardly from said guide members; means preventing lateral movement of said brackets; and means on said brackets for positioning in the rear of said carriage the article to be sprayed.

11. The combination of two vertical guide members provided with a plurality of vertical sets of bolt sockets, the sockets in each vertical set being spaced apart differently from those in the other sets; bearings for the ends of said guide members in which said members may be rotated about their vertical axes; a tie between the lower bearing members; means preventing rotation of the upper bearing members; a carriage movable vertically between said guide members; spring-pressed bolts at the opposite ends of said carriage adapted to coact with said sockets; means for withdrawing said bolts; and an air brush support movable horizontally on said carriage.

12. The combination of two vertical guide members provided with a plurality of vertical sets of bolt sockets, the sockets in each vertical set being spaced apart differently from those in the other sets; bearings for the ends of said guide members in which said members may be rotated about their vertical axes; struts extending from the upper bearing members to a fixed support; a carriage movable vertically between said guide members; spring-pressed bolts at the opposite

ends of said carriage adapted to coact with said sockets; means for withdrawing said bolts; and an air brush support movable horizontally on said carriage.

13. The combination of two vertical guide members provided with a plurality of vertical sets of bolt sockets, the sockets in each vertical set being spaced apart differently from those in the other sets; bearings for the ends of said guide members in which said members may be rotated about their vertical axes; a carriage movable vertically between said guide members; rollers supported upon the upper bearing members; flexible members secured at one end to said carriage and extending over said rollers; counterweights secured to the opposite ends of said flexible members; spring-pressed bolts at the opposite ends of said carriage adapted to coact with said sockets; means for withdrawing said bolts; and an air brush support movable horizontally on said carriage.

14. The combination of two vertical guide members provided with a plurality of vertical sets of bolt sockets, the sockets in each vertical set being spaced apart differently from those in the other sets; bases having bearings for the lower ends of said vertical guide members in which said members may be rotated about their axes; and a locking member mounted upon each base and coacting with a guide member to prevent its rotation.

15. The combination of two vertical guide members provided with a plurality of vertical sets of bolt sockets, the sockets in each vertical set being spaced apart differently from those in the other sets; bases having bearings for the lower ends of said vertical guide members, in which said members may be rotated about their axes, means for locking said guide members in adjusted position; two brackets, each having a hub surrounding a guide member; collars at opposite ends of the hubs pinned to said guide members; tie rods connecting the two brackets; and a locking member mounted upon each base and coacting with a guide member to prevent its rotation.

16. The combination of two vertical guide members provided with a plurality of vertical sets of bolt sockets, the sockets in each vertical set being spaced apart differently from those in the other sets; bases having bearings for the lower ends of said vertical guide members, in which said members may be rotated about their axes; means for locking said guide members in adjusted position; two brackets, each having a hub surrounding a guide member; collars at opposite ends of the hubs pinned to said guide members; tie rods connecting the two brackets; and a series of pins extending upwardly from each bracket.

17. The combination of two vertical guide

members provided with a plurality of vertical sets of bolt sockets, the sockets in each vertical set being spaced apart differently from those in the other sets; bases having bearings 10 for the lower ends of said vertical guide members, in which said members may be rotated about their axes; means for locking said guide members in adjusted position; two brackets, each having a hub surrounding a guide member; collars at opposite ends of the hubs pinned to said guide members; tie rods connecting the two brackets; a series of pins extending upwardly from each bracket; and a brace from the outer end of each bracket to 15 one of said bases.

18. In a spraying machine, a carriage composed of two end members having pins at opposite end thereof and two cup-shaped depressions; two tubes with their ends in said 20 depressions; rods extending through said tubes and connecting said end members; and rollers mounted on said pins.

19. In a spraying machine, a carriage composed of two end members having pins at 25 opposite ends thereof and two cup-shaped depressions; two tubes with their ends in said depressions; rods extending through said tubes and connecting said end members; rollers mounted on said pins; a bolt extending 30 through each end member, a collar thereon; a spring between said collar and the outer face of said end member; and means connected to the inner end of said bolt whereby said spring may be compressed and said bolt 35 moved inwardly.

20. In a spraying machine, an airbrush support consisting of a spider having four rollers revolutely mounted in the ends of its legs and provided with a downward extension; 40 a member revolutely mounted in said extension and depending therefrom; and means for clamping an air brush to said member.

21. In a spraying machine, an air brush support consisting of a spider having four rollers revolutely mounted in the ends of its legs and provided with a downward extension with a cylindrical socket; a member having a trunnion revolutely mounted in the socket of said extension; and means for 45 clamping an air brush to said member.

22. In a spraying machine, an air brush support consisting of a spider having four rollers revolutely mounted in the ends of its legs and provided with a downward extension; 50 a member having a trunnion revolutely mounted in said extension and depending

therefrom; a screw in said extension having a reduced inner end disposed in an annular groove in said trunnion; and means for 55 clamping an air brush to said member.

23. The combination of two vertical guide members; a carriage movable vertically thereon and having parallel guides; balancing weights for said carriage; means for locking the opposite ends of said carriage directly to said guide members; and an air 60 brush support movable horizontally between the parallel guides of said carriage.

24. The combination of two parallel guide members; a carriage movable lengthwise 70 thereof and having parallel guides; means for locking the opposite ends of said carriage directly to said guide members; and an air brush support adapted to be moved manually lengthwise of said carriage.

25. The combination of two parallel guide members; a carriage movable lengthwise thereof; means for locking the opposite ends of said carriage directly to said guide members; and an air brush support movable 80 lengthwise of said carriage.

26. The combination of two parallel guide members; a carriage movable lengthwise thereof; means for locking the opposite ends of said carriage directly to said guide members; an air brush support movable lengthwise of said carriage; and means secured to 85 the rear of said guide members for supporting an article to be sprayed.

27. The combination of two parallel guide members; a carriage movable lengthwise thereof; means for locking the opposite ends of said carriage directly to said guide members; an air brush support movable lengthwise of said carriage; and means secured to 95 the rear of said guide members for supporting an article to be sprayed at different distances from said air brush support.

28. The combination of two parallel guide members; a carriage movable lengthwise 100 thereof; means for locking the opposite ends of said carriage directly to said guide members; an air brush support movable lengthwise of said carriage; brackets extending rearwardly from said guide members; and 105 means for positioning on said brackets an article to be sprayed.

Signed by me at 746 Old South Bldg., Boston, Massachusetts, this 4th day of August, 1927.

PHILIP G. AULSON.
